UNITED STATES PATENT OFFICE

FURMAN M. KANDLE, OF ATLANTIC CITY, NEW JERSEY

FURNACE GRATE

Application filed March 19, 1928. Serial No. 262,679.

This invention relates to an improved furnace grate, and one which comprises a plurality of tiltable grate bars so connected that the movement of a member for actuating one 5 grate bar, will operate all the bars in unison correspondingly, and will in turn cause tilting action of intervening grate bars, which are provided with openings, which openings with those in the first grate bars will permit 10 the ashes to pass therethrough and into the ash pit, the latter grate bars resting on and intervening the first grate bars, whereby it is possible to burn a fine grade of coal, such as buckwheat and rice coal in furnaces, enabling the ashes to pass through and yet retain 15 a substantial bed of hot coals.

Another purpose is to provide a furnace grate, which is an improvement over the construction and arrangement of furnace grate 20 in the application filed in the name of Furman M. Kandle, August 1, 1927, Serial No. 209,986, which has now matured into United States Letters Patent No. 1,728,126, dated September 10, 1929.

25 A still further purpose is to provide a furnace grate wherein the grate bars which rest on and are disposed intervening the connected operating grate bars are provided with depending fins, which act to keep the grate bars 30 in position. The fins are in the form of blades extending longitudinally of the auxiliary grate bars.

35 A still further purpose is a provision and means interconnecting the auxiliary grate bars with the main grate bars, in order to insure movement between all the bars.

It is to be understood that the particulars herein given are in no way limitive, and that 40 while still keeping within the scope of the invention, any desired modification of details and proportions may be made in the construction of the appliance according to circumstances.

The invention comprises further features 45 and combination of parts to be hereinafter set forth, shown in the drawings and claimed.

In the drawings:

Figure 1—is a plan view of a main grate of 50 a furnace showing the auxiliary grate bars in position.

Figure 2—is a partial sectional view on line 2—2 of Figure 3.

Figure 3—is a sectional view on line 3—3 of Figure 1.

Figure 4—is a similar detailed sectional 55 view showing the bars tilted.

Figure 5—is a sectional view of a modified form of the main and auxiliary grate bars, showing the inter-connections between the 60 main and auxiliary bars.

Figure 6—is a bottom plan view of the auxiliary grate.

Referring to the drawings, 1 identifies a main frame of the grate, which may be any shape or size preferably rectangular, and mounted in bearings in the frame are transverse rocking rods 2, on which transverse grate bars 3 are mounted to move with the rods. Certain ends of the rods have lateral arms 4, which are connected by a bar 5, and one of the rods, preferably the center one, is squared on its end to receive a crank handle not shown whereby the several grate bars 3 may be rocked. The fact is the rocking of the center grate bar in turn transmits rocking movement to the other bars. The grate bars 3 have transverse openings and arms 6 and 7 to permit the ashes to pass therethrough when the grate bars are rocked. 75

Resting on the grate bars and intermediate 80 the transverse rods are auxiliary grate bars 8, which are arcuate or curved in cross section.

The auxiliary grate bars 8 have transverse openings 9, which also act to permit the ashes to pass therethrough when the bars are 85 shaken. Depending from the auxiliary grate bars and positioned intermediate the adjacent edges of the grate bars 3 are fins 10, which have U-shaped cuts or grooves 11 on their opposite faces, which are disposed in positions incident to the openings in the auxiliary grate bars, making it possible to cut the grate bars easily into various lengths. For instance in making the auxiliary grate bars they may be made of the maximum 90 length and to provide for shorter auxiliary grate bars, they may be cut at the points where the openings and the grooves or channels 11 occur. The openings and the channels 11 being incident to each other provide 95

100

for less material in cutting through the bars.

Referring to Figure 5 it will be noted that the main grate bars are slightly modified in shape cross sectionally. These main grate bars 12 have three wings, two of the wings being arranged at an obtuse angle instead of the two wings being flat as in Figures 1 to 4, the depending wing extending downwardly from the center part of the grate bar, that is at its rocking point.

Also in Figure 5 the auxiliary grate bars 13 have a depending fin 14, and they so overlie the two wings of the main grate bar as to impart movement to the auxiliary bars when the main bars are rocked, there being U-shaped couplings 15 carried by the auxiliary grate bars and passing through the openings 16 in certain of the wings of the main grate bars, thereby inter-connecting the various bars to insure their proper relative movements.

When one of the main grate bars is rocked movement is imparted to the rest of the main bars, and as they operate they kick or engage with the auxiliary bars and impart movement to them, the fins 10 and 14 acting to insure this movement and also act as balance members for the auxiliary bars.

The invention having been set forth, what is claimed is:

1. In a furnace grate, the combination with main grate bars with means to operate them in unison, of auxiliary grate bars supported only by the adjacent portions of the main grate bars at points to one side of the centers thereof, and fins depending from the auxiliary grate bars to aid balancing them.

2. In a furnace grate, a plurality of main grate bars including means for imparting rocking movement thereto, a plurality of auxiliary grate bars supported only by the adjacent portions of the main grate bars at points to one side of the centers thereof and designed to be moved by the main grate bars, said auxiliary grate bars having depending fins intervening the adjacent portions of the main grate bars, said auxiliary bars being adapted to agitate the lower part of the bed of the fire, said fins acting as means to balance the auxiliary grate bars in their positions.

3. In a furnace grate, a plurality of main grate bars including means for imparting rocking movement thereto, a plurality of auxiliary grate bars supported only by the adjacent portions of the main grate bars at points to one side of the centers thereof and designed to be moved by the main grate bars, said auxiliary grate bars having depending fins intervening the adjacent portions of the main grate bars, said auxiliary bars being adapted to agitate the lower part of the bed of the fire, said fins acting as means to balance the auxiliary grate bars in their posi-

tions, and means connecting the main and auxiliary grate bars.

In testimony whereof he affixes his signature.

FURMAN M. KANDLE.
